(57) **CLAIM**

We claim the ornamental design for a knock down bracket, as shown and described.

DESCRIPTION

FIG. 1 is a front right side perspective view of a knock down bracket. The front left side perspective view being a mirror image thereof;

FIG. 2 is a side elevational view thereof, the view from the opposite side being a mirror image thereof;

FIG. 3 is front elevational view thereof;

FIG. 4 is a top plan view thereof;

FIG. 5 is a bottom plan view thereof; and,

FIG. 6 is rear left side perspective view thereof.

The broken lines shown are included for the purpose of illustrating portions of the knock down bracket that form no part of the claim.
